L. M. BARMAN

STENCIL CARD DRAWER OR CONTAINER FOR USE WITH ADDRESSING MACHINES

Filed June 9, 1923

FIG. 1.

FIG. 2.

FIG. 3.

FIG. 4.

FIG. 5.

FIG. 6.

INVENTOR

Louis Maurice Barman
By Richards, Gleec
Atty.

UNITED STATES PATENT OFFICE.

LOUIS MAURICE BARMAN, OF LONDON, ENGLAND.

STENCIL-CARD DRAWER OR CONTAINER FOR USE WITH ADDRESSING MACHINES.

Application filed June 9, 1923. Serial No. 644,512.

To all whom it may concern:

Be it known that I, LOUIS MAURICE BARMAN, a citizen of the United States of America, residing at Roneo Building, 5 Holborn, 5 London, E. C. 1, England, Great Britain, have invented new and useful Improvements in and connected with Stencil-Card Drawers or Containers for Use with Addressing Machines, of which the following is a specification.

The present invention relates to improvements in and connected with stencil card drawers or containers for use with addressing machines.

15 Drawers for holding stencil cards have been used in connection with addressing machines the said drawers being adapted to transfer the stencil cards to the hopper or magazine and then be supported from the 20 machine to act as hoppers for the used stencils.

With such drawers no adequate provision has been made for locking the stencil cards into the drawer previous to transferring the 25 said cards to the hopper or magazine, with the result that there is the risk in carrying a drawer, complete with its stencil cards, from a cabinet to the addressing machine, and subsequently transferring the cards to 30 the hopper or magazine that the proper sequence of the cards may be disturbed through careless manipulation.

Moreover, a drawer with its stencil cards 35 is of considerable weight, and unless some provision is made for preventing accidental displacement of the cards it is possible that the operator may be put to considerable loss of time in the event of the container being dropped.

40 Now, the object of the present invention is to so construct the drawer or container that the stencil cards are retained and locked therein against movement up to and during the initial stage of transfer to the hopper or magazine.

A further object of the invention consists in the utilization of the means for retaining the stencil cards against movement as a reversible side wall of the drawer.

45 According to the invention, the drawer or container for the stencil cards is constructed from metal, or other suitable material and is formed with a fixed base, one side wall and two ends, the top as well as one side being normally open, unless one or the other 55 is partially closed by the locking device.

To the front and rear of the drawer is attached or formed therefrom a pair of lugs extending outwardly and upwardly from the drawer. Supported between the lugs as by 60 means of a hinge or the like is a flap provided with a bead or curved edge at its extremity, the said flap with its bead extending the entire length of the drawer.

To the other end of the hinge is applied a 65 flat spring, the end of which is provided with a pin adapted to register in holes or perforations made in the front of the drawer so as to control the position of the flap.

The invention will now be described with 70 reference to the accompanying drawings, whereon:—

Fig. 1 is a plan view of a drawer or container adapted for use with addressing machines.

Fig. 2 is a cross-sectional view looking 75 towards the rear of the drawer.

Fig. 3 is a front view of the drawer with the locking device in position.

Fig. 4 is a side view showing the locking 80 device as forming a partial side of the drawer.

Fig. 5 is a front view showing the locking device moved into a position whereby one 85 side is completely open.

Fig. 6 is a rear view of the drawer or container.

As will be seen from the drawings the drawer or container consists of a base *a*, one side wall *b*, the front *c* and the back *d*, the 90 top or one side being partially closed, at will, by means of the locking device. To the front wall *c* and the rear wall *d* is attached or formed therefrom a pair of lugs *e* *e'* extending outwardly and upwardly from 95 the drawer. Supported between the lugs as by means of a hinge *g* or the like is a flap *f* provided with a bead or curved edge *f'* at its extremity the said flap, with its bead extending the entire length of the drawer.

As shown on the drawings, Figs 1, 4 or 6 the flap *f* may be provided with a lug *h* carrying a pin *i* to which is secured one end of a spring *j* the other end of the said spring being attached to a stud *k* secured to the 100 back of the drawer.

As shown on the drawings, Figs. 1, 3, 4 and 5, a short lever *l* is secured to the hinge or pin *g*, the free end of the said lever being bored out to receive a spring pressed pin *m* 110 carried in a thumb nut *n* the end of the pin *m* engaging one or other of two holes or per-

forations o (Fig. 3) formed in the front c of the drawer.

As will be seen from the drawings when the flap f is brought by means of the thumb nut n to the position shown in Fig. 2 the bead f^1 enters notches p formed in the edges of the stencil cards g in the manner shown in Fig. 2 and the stencil cards are thereby locked in the drawer.

10 When, however, the pin m fitting in the thumb nut n is pulled out of the perforation and the lever l is afforded a downward turning movement, the pin m engages the second hole or perforation o (Fig. 3) and in this 15 position the bead f^1 is clear of the notches p cut out of the stencils g .

Each drawer with its load of stencils is put into a cabinet with the stencils locked in the drawer in the manner described. 20 When it is desired to use the stencil cards with an addressing machine, a drawer is removed with the locked stencils from the cabinet and is brought to the machine. At this stage, the bead or curved edge f^1 is removed from its locking position by bringing the pin m to the second hole or perforation o , and the stencil cards are then free to be removed.

It is to be understood that varying methods 30 of transferring the stencil cards g from the drawer to the hopper or magazine of the addressing machine may be necessary having regard to the particular type of hopper used.

For example, in the case of a hopper comprising two sides or walls, each wall being 35 fixed to the base plate of the machine, batches of stencil cards may be removed by hand and stacked in the hopper, and the drawer or container may be supported from the end 40 of the machine in such a manner that each card, after use, will fall back into the drawer in the order of removal therefrom.

When the drawer or container is supported at the end of the machine on a moving platform 45 the pin m is removed from the non-locking perforation or hole o and the flap f is turned over by the thumb nut n until the back surface of the flap f rests upon the top of the drawer, as see Fig. 5. The drawer is then 50 mounted upon the moving support in such a manner that the open side becomes the receiving side for the used stencils, and the top of the drawer or container, is closed by the flap f .

After the stencils are returned to the 55 drawer, the flap f is turned round by the thumb nut n until the pin m enters the locking hole o whereby the stencils g are locked and are carried to the cabinet for storing.

From the invention thus described it will 60 be seen that adequate provision is made for preventing displacement of the cards, during removal from the cabinet to the addressing machine since by the present invention the cards remain securely locked in position until it is required to transfer them to the hopper or magazine.

The locking device with its operating features may be varied to suit special conditions without departing from the spirit 70 of the invention.

In some cases, as for example when drawers of large size are employed, the lugs $e e^1$ may be dispensed with, and the hinge or pivot g may be supported between the front 75 c and the back d of the drawer.

Having thus described my invention what I desire to secure by Letters Patent of the United States is as follows:—

1. In drawers for stencil cards for use 80 with addressing machines, the combination with stencil cards having grooves formed therein; of a container, a member pivotally connected to said container and having a free curved edge, and means for moving said member about its pivot so that said curved edge will enter the grooves formed in the stencil cards within the container.

2. Drawers for stencil cards for use with addressing machines including a container 90 having an open side and perforations in the front thereof, lugs projecting from said container, a pin carried in said lugs, a locking member supported in said pin and capable of partially closing said open side, 95 and a locking pin engageable in said perforations.

3. In drawers for stencil cards for use with addressing machines, the combination with stencil cards having grooves formed 100 therein; of a container for said cards, and a locking device carried by said container and capable of engagement in the grooves in said cards for retaining the latter in the container.

In testimony whereof I have signed my name to this specification.

LOUIS MAURICE BARMAN.
